TREATMENT OF HYDROCARBON OIL

George W. Miller, Jackson Heights, N. Y., assignor
to Universal Oil Products Company, Chicago,
Ill., a corporation of South Dakota

Application July 29, 1932, Serial No. 625,906

6 Claims. (Cl. 196—51)

This invention relates more particularly to an improved method and means of handling the polymer condensate resulting from the polymerization treatment of cracked hydrocarbon oil vapors direct from a cracking operation to increase the efficiency and yields of the cracking operation.

In the treatment of hydrocarbon oil vapors with polymerizing material such as contact clays, fuller's earth and the like, a condensate containing the polymers is separated from the treated vapors. This product is known in the industry and will be hereinafter referred to as polymer condensate. The polymerization treatment of light vaporous products direct from the fractionator of a hydrocarbon oil cracking process has recently come into commercial prominence and it has been proposed to dispose of the polymer condensate resulting from such treatment by returning it to the heating coil of the cracking system together with raw oil charging stock and reflux condensate from the fractionator of the cracking system for the purpose of increasing the yields of desirable light products.

It has been found that this method of handling the polymer condensate may result in the accumulation of excessive quantities of coke or carbonaceous material in the heating coil, due to the inability of the heavy polymers to withstand the conversion conditions required for the treatment of the other materials (raw oil and reflux condensate) supplied to the same heating coil without excessive cracking of the heavy polymers and the resulting formation therefrom of high yields of coke and gas. This, of course, is true regardless of whether the polymers are returned direct to the heating coil or to the fractionator of the cracking system, as in the latter case the heavy polymers are eventually supplied to the heating coil together with reflux condensate from the fractionator.

In cracking processes of the character wherein residual oil from the reaction chamber of the cracking system, alone or together with vaporous products from the same reaction zone, is subjected to further vaporization at reduced pressure, it has been attempted to overcome coking difficulties in the heating coil of the system by returning the polymer condensate to said reduced pressure chamber. It has been found, however, that the mild conditions existing in this reduced pressure zone do not effect sufficient further conversion of the polymer condensate.

The present invention obviates the difficulties formerly encountered in the return of polymer

condensate to the cracking system by separating the polymer condensate into light and heavy fractions, withdrawing the heavy or high boiling fractions, containing the heavy coke-forming polymers, from the system, alone or together with residual liquid conversion products produced by the cracking operation, and returning the lower boiling fractions, which are substantially free of coke-forming polymers, for further conversion by supplying them either to the fractionator or direct to the heating coil of the cracking system.

As a further special feature of the present invention, when utilized in conjunction with that type of cracking system wherein residual liquid conversion products or both vaporous and residual liquid conversion products are withdrawn through a common outlet from a high pressure reaction chamber to further vaporization in a zone of reduced pressure, all or a portion of the low boiling fractions of the polymer condensate may be blended with the conversion products passing from the reaction chamber to the reduced pressure vaporizing chamber, serving as a diluent and cooling medium and being subsequently vaporized in the vaporizing chamber, passed to the fractionator of the cracking system, condensed therein together with the reflux condensate and returned therewith to the heating coil for further conversion.

Any distillate within the boiling range of the desired final motor fuel product of the system contained in the low boiling fraction of the polymer condensate will, of course, pass overhead with the vapors from the fractionator to further polymerization treatment, condensation and collection when said low boiling fraction of the polymer condensate is returned to the fractionator or to the vaporizing chamber. On the other hand, when this fraction is returned direct to the heating coil its components of motor fuel boiling range may be subjected to further conversion in the cracking zone of the system whereby their anti-knock value may be improved, particularly when relatively severe conversion conditions are utilized in the heating coil.

The accompanying diagrammatic drawing illustrates one specific form of apparatus for carrying out the invention. It should be understood, however, that the features of the invention may be applied to any type of cracking system and are not limited to the one here illustrated and described, nor are they limited to the particular form of apparatus shown in conjunction with the cracking system.

Referring to the drawing, raw oil charging

stock for the cracking system is supplied through line 1 and valve 2 to pump 3 from which it may be fed through line 4, valve 5 and line 6 direct to heating coil 7 or through line 8 and valve 9 into fractionator 10, to be preheated therein by direct contact with the ascending vapors in this zone, assisting their fractionation and passing, together with the reflux condensate separated from the vapors in the fractionator, through line 11 and valve 12 to pump 13 from which the reflux condensate, or reflux condensate and preheated raw oil, is supplied through line 6 and valve 14 to heating coil 7. The raw oil may, of course, be preheated, all or in part, by any other well known means (not shown) prior to its introduction into the heating coil.

The oil supplied to heating coil 7 is heated to the desired conversion temperature preferably at substantial superatmospheric pressure by means 20 of heat supplied from a furnace 15 of any suitable form and the heated oil is discharged from the heating coil through line 16 and valve 17 into reaction chamber 18, which is also preferably maintained at substantial superatmospheric 25 pressure.

Reaction chamber 18 preferably is heavily insulated or may, when desired, be externally heated, although insulation and heating means are not shown in the drawing, to prevent the excessive loss of heat through the walls of the chamber by radiation so that the heated oil introduced into this zone, and particularly the vaporous conversion products, are subjected to continued conversion during their passage 35 through the reaction chamber.

In the particular form of cracking system here illustrated, both vaporous and residual liquid conversion products are withdrawn from the lower portion of the reaction chamber in 40 commingled state through line 19 and valve 20 and are introduced into a vaporizing chamber 21 which is preferably maintained at substantially reduced pressure relative to that employed in chamber 18 by means of which further vaporization of the residual liquid withdrawn from chamber 18 is effected. Residual liquid remaining unvaporized in chamber 21 may be withdrawn therefrom to cooling and storage or to any desired further treatment through line 22 and 45 valve 23 or, when desired, conditions may be so controlled in chamber 22 that substantially no liquid residue is produced, the residual products of the system being reduced to coke in this zone, in which case the coke may be allowed to accumulate within chamber 21 to be removed therefrom after its operation is completed. A plurality of coking chambers similar to chamber 21, but not illustrated in the drawing, may be employed, when desired, and may be operated 50 either alternately or simultaneously to provide additional space for the accumulation of coke and permit prolonged operation of the process.

Vaporous products are withdrawn from chamber 21 through line 24 and valve 25 to fractionation in fractionator 10 wherein their insufficiently converted heavy components are condensed as reflux condensate to be returned, as already described, to heating coil 7 for further conversion.

Vaporous products of the desired end-boiling 70 point, remaining uncondensed in fractionator 10, are withdrawn from its upper portion through line 26 and may pass through line 27 and valve 28 into polymer treating chamber 29 or through line 27' and valve 28' into polymer treating chamber 29'.

The treating chambers 29 and 29' are similar zones each containing a bed of polymerizing material, such as fuller's earth or contact clay, through which the fractionated vapors are passed, preferably in a downward direction. 5 Provision is made, in the case illustrated, for operating the chambers either in series or in parallel. When parallel flow is employed, vapors from the fractionator may enter each of the chambers through the lines 27 and 27', as described, the treated vapors and the polymers formed by their passage through the beds of treating material being removed from chambers 29 and 29', respectively, through lines 30 and 30', controlled by the respective valves 31 and 31'. When the polymer treating chambers are operated in series the vapors from fractionator 26 may, for example, enter chamber 29 through line 27 and valve 28, the polymers formed being separated in the lower portion of this chamber 20 and the vapors passing through line 32 and valve 33 into the upper portion of chamber 29', in which case the treated vapors and polymers formed in chamber 29' may be withdrawn through line 30' and valve 31' and commingled 25 in line 34 with polymers withdrawn from the lower portion of chamber 29 through line 30 and valve 31.

The treated vapors and polymerization products from chambers 29 and 29' pass through line 34 into distilling and fractionating column 35 wherein the polymers are subjected to reheating and vaporization and the vapors are fractionated for the removal of polymerization products therefrom. Treated vapors of the desired end-boiling point, substantially freed of polymerization products by fractionation, are withdrawn from the upper portion of the fractionator through line 36 and valve 37, are subjected to condensation and cooling in condenser 38, from which the resulting distillate and uncondensable gas is withdrawn through line 39 and valve 40 to collection in receiver 41. Uncondensable gas may be released from the receiver through line 42 and valve 43. Distillate may be withdrawn from receiver 41 through line 44 and valve 45. A portion of the distillate collecting in receiver 41 may, when desired, be recirculated, by well known means (not shown) to either or both fractionators of the system to assist fractionation and to maintain the 50 desired vapor outlet temperature from each of these zones. Well known means (not shown) may also be provided for returning a portion of this product to chambers 29 and 29' into which it may be sprayed as a washing medium to wash 55 polymerization products from and revive the treating material.

A heating or reboiling coil 46 may be provided in the lower portion of distilling and fractionating column 35 through which any suitable heating 60 medium such as steam or hot vaporous or liquid products of the process are passed for the purpose of reboiling the polymer condensate which collects in this zone and vaporizing all but its heavy components of high coke-forming characteristics. 65

The heavy polymers remaining unvaporized in the lower portion of column 35 are withdrawn therefrom through line 47 and may be removed from the system through line 48 and valve 49 or may pass, all or in part, through line 47 and valve 70 50 to pump 51 from which they are fed through line 52, line 66 and valve 67 into line 22 to blend with the residual liquid conversion products withdrawn from chamber 21 and be collected there- 75 with as a portion of the final residual liquid prod-

uct of the system. Blending of the polymers and cracked residue to form a single heavy liquid product is, of course, only practiced when chamber 21 is operated for the production of liquid residue. When coking of the residual conversion products is employed in chamber 21 the heavy polymers may pass through valve 53, in line 52, into chamber 21 wherein they may also be subjected to coking.

10 The treated vapors entering column 35 from chambers 29 and 29' pass together with the light fractions of the polymer condensate vaporized, as already described, in the lower portion of column 35, into the upper or fractionating portion of the 15 column which is separated from the lower or re-boiling section by a suitable partition or tray 54. Vaporized fractions of the polymer condensate, not suitable as a portion of the final light distillate product of the system but lighter than the 20 high coke-forming polymers remaining unvaporized in the lower section of column 35, are condensed by fractionation in the upper section of the column and collect as light polymer condensate above the tray or partition 54, to be withdrawn 25 therefrom through line 55 and valve 56 to pump 57, by means of which it is returned to the cracking system for further conversion in any one or any combination of several manners. All or any portion of the light polymer condensate may pass 30 from pump 57 through line 58, valve 59 and line 6 direct to heating coil 7, or may be diverted from line 58 through line 60 and valve 61 into fractionator 10 wherein they may serve as a cooling 35 means to assist fractionation of the vapors, passing therefrom, together with reflux condensate, to heating coil 7 for further conversion.

As a special feature of the invention, a portion or all of the light polymer condensate may be blended with the stream of conversion products passing from chamber 18 to chamber 21, serving as a diluent and cooling medium to assist in preventing excessive conversion and the formation of coke in the lower portion of chamber 18 and in line 19. The light polymer condensate used for this purpose may be blended, all or in part, with the conversion products in the lower portion of chamber 18 by passing it through line 62 and valve 63 into the lower portion of the reaction chamber or may be blended, 50 all or in part, with the material passing from chamber 18 to chamber 21 through line 19 by passing it through line 64 and valve 65 into line 19 or any other well known means may be employed, although not illustrated in the drawing, 55 such as, for example, spraying the polymer condensate against the walls of reaction chamber 18. In any case, the light polymer condensate blended with the conversion products introduced into chamber 21 are heated by direct contact therewith and thereby subjected to a temperature which may be sufficient to effect its mild conversion. Any fractions of the polymer condensate sufficiently light to escape the desired 60 degree of conversion by blending with the hot conversion products from chamber 18, as described, but higher boiling than the desired motor fuel product of the system, will be condensed in fractionator 10 and returned therefrom to heating coil 7 for further more severe conversion. 65 At the same time any heavy residual products resulting from conversion of the polymer condensate, blended with the conversion products from chamber 18, separate from the lighter conversion products in chamber 21 and blend with 70 the other residual conversion products of the 75

system to be withdrawn as residual liquid from chamber 21 or reduced to coke in this zone.

It will be evident to one skilled in the art that many modifications of the specific form of apparatus illustrated and above described may be employed without departing from the scope of the invention. For example, treated vapors and polymer condensate may be separately withdrawn from the treating chambers in the usual manner instead of being withdrawn in commingled state. The treated vapors may then be subjected to fractionation for the removal of additional polymer condensate and all of the polymer condensate may be collected, subjected to redistillation or reboiling and fractionation for separation into light and heavy fractions, which fractions may then be handled in the manner prescribed. It is therefore not intended to limit the invention to any specific form of apparatus, the main feature of the invention 10 being the separation by any means of light and heavy fractions of the polymer condensate and the return of only the light fractions to further conversion in the heating coil of the same cracking system, wherein the vapors subjected to 15 polymerization treatment are produced.

Inasmuch as the features of the present invention are adaptable to nearly any type of cracking system any desired conversion conditions 20 may be employed, however, in the particular type of system here illustrated and above described, conversion temperatures ranging from 875 to 975° F. with a superatmospheric pressure of from 100 to 800 pounds, or thereabouts, per 25 square inch are preferably employed at the outlet from the heating coil. A superatmospheric pressure within substantially this same range is preferred in the reaction chamber and the pressure is preferably reduced in the vaporizing 30 chamber and in succeeding portions of the cracking system, said reduced pressure ranging, for example, from 100 pounds, or thereabouts, per square inch down to substantially atmospheric 35 pressure. When desired, reduced pressure may be employed in the distilling and fractionating 40 column to which the polymer condensate is supplied, relative to that in the treating chambers, to assist vaporization of the polymer condensate. The exact conditions employed in the distilling 45 and fractionating column will vary with different charging stocks and different operating conditions in the cracking portion of the system. Preferably, however, reboiling and fractionation 50 are so controlled in this zone that that fraction 55 of the polymer condensate returned to the fractionator or direct to the heating coil of the cracking system for further conversion has an end-boiling point no higher than the end-boiling point of the combined feed (raw oil and reflux 60 condensate from the fractionator of the cracking system) which is supplied to the same heating coil and the vaporous product withdrawn 65 from the upper portion of this column has an end-boiling point corresponding to the desired end-boiling point of the final light distillate 70 product of the system. For example, with the distilling fractionating column operated at substantially atmospheric pressure, the polymers may be reheated in the lower portion of this column to a temperature ranging from 500 to 700° F., or thereabouts, and the vaporous products may be withdrawn from the upper portion 75 of the column at a temperature of 350 to 437° F., or thereabouts.

I claim as my invention:

1. In a process for the treatment of hydrocarbon oil wherein an oil is subjected to conversion temperature at superatmospheric pressure in a heating coil and communicating enlarged reaction chamber, liquid and vaporous conversion products are withdrawn from the reaction chamber to a reduced pressure vaporizing chamber, unvaporized residual liquid is withdrawn from the vaporizing chamber, vaporous products from the vaporizing chamber are subjected to fractionation, the heavy components of the vapors, condensed by fractionation, are returned to the heating coil for further conversion and fractionated vaporous products of the desired end-boiling point are subjected to refining by polymerization treatment, whereby polymer condensate containing gum and color-forming compounds and also containing desirable light components is formed, the improvement which comprises subjecting said polymer condensate to further heating for the removal therefrom of desirable light components and separation of the remaining portion into light and heavy fractions, withdrawing said heavy fractions from the system and returning said last mentioned light fractions, without prior heating thereof to cracking temperature, to the reaction chamber for further conversion.
2. In a process for the treatment of hydrocarbon oil wherein an oil is subjected to conversion temperature at superatmospheric pressure in a heating coil and communicating enlarged reaction chamber, liquid and vaporous conversion products are withdrawn from the reaction chamber to a reduced pressure vaporizing chamber, unvaporized residual liquid is withdrawn from the vaporizing chamber, vaporous products from the vaporizing chamber are subjected to fractionation, the heavy components of the vapors, condensed by fractionation, are returned to the heating coil for further conversion and fractionated vaporous products of the desired end boiling point are subjected to refining by polymerization treatment with fuller's earth whereby polymer condensate containing gum and color-forming compounds and also containing desirable light components is formed, the improvement which comprises subjecting said polymer condensate to further heating for the removal therefrom of desirable light components and separation of the remaining portion into light and heavy fractions, withdrawing said heavy fractions from the system and returning said last mentioned light fractions, without prior heating thereof to cracking temperature, to the reaction chamber for further conversion.
3. In a process for the treatment of hydrocarbon oil wherein an oil is subjected to conversion temperature at superatmospheric pressure in a heating coil and communicating enlarged reaction chamber, liquid and vaporous conversion products are withdrawn from the reaction chamber to a reduced pressure vaporizing chamber, unvaporized residual liquid is withdrawn from the vaporizing chamber, vaporous products from the vaporizing chamber are subjected to fractionation, the heavy components of the vapors, condensed by fractionation, are returned to the heating coil for further conversion and fractionated vaporous products of the desired end-boiling point are subjected to refining by polymerization treatment with an adsorbent earth, whereby polymer condensate containing gum and color-forming compounds and also containing desirable light components is formed, the improvement which comprises subjecting said polymer condensate to further heating for the removal therefrom of desirable light components and separation of the remaining portion into light and heavy fractions, withdrawing said heavy fractions from the system and returning said last mentioned light fractions, without prior heating thereof to cracking temperature, to the reaction chamber for further conversion.
4. In a process for the treatment of hydrocarbon oil wherein an oil is subjected to conversion temperature at superatmospheric pressure in a heating coil and communicating enlarged reaction chamber, liquid and vaporous conversion products are withdrawn from the reaction chamber to a zone of reduced pressure, vaporous products are withdrawn from the reduced pressure zone and subjected to fractionation, the heavy components of the vapors, condensed by fractionation, are returned to the heating coil for further conversion and fractionated vaporous products of the desired end-boiling point are subjected to refining by polymerization treatment, whereby polymer condensate containing gum and color-forming compounds and also containing desirable light components is formed, the improvement which comprises subjecting said polymer condensate to further heating and fractionation for the removal therefrom of desirable light components, and separation of the remaining portion into light and heavy fractions and returning said light fractions, without prior heating thereof to cracking temperature, to the reaction chamber of the cracking system for further conversion.
5. In a hydrocarbon oil cracking process of the character wherein the oil is heated to cracking temperature under pressure while flowing in a restricted stream through a heating zone and thence discharged into an enlarged reaction zone maintained under cracking conditions of temperature and pressure wherein further conversion of the oil occurs, the method which comprises subjecting the gasoline vapors produced by the cracking to a polymerization treatment thereby forming polymer condensate, separating the latter into a light fraction and a heavy fraction, introducing at least a portion of said light fraction, without prior heating thereof to cracking temperature, into the reaction zone and commingling the same therein with the heated oil discharged from the heating zone, and withdrawing said heavy fraction from the system.
6. A conversion process which comprises subjecting hydrocarbon oil in a cracking zone to cracking temperature under sufficient superatmospheric pressure to maintain a substantial portion thereof in liquid phase, removing both vapors and unvaporized oil as a mixture from the cracking zone and discharging the same into a flashing zone maintained under lower pressure than the cracking zone, separating said mixture into vapors and residue in the flashing zone, fractionating the vapors to condense fractions thereof heavier than gasoline, subjecting the uncondensed gasoline vapors to a polymerization treatment, thereby forming polymer condensate, separating the latter into a light fraction and a heavy fraction, returning the light fraction to the cracking zone for cracking treatment therein and introducing said heavy fraction directly, and without prior cracking treatment thereof, to the flashing zone.

CERTIFICATE OF CORRECTION.

Patent No. 2,055,085.

September 22, 1936.

GEORGE W. MILLER.

It is hereby certified that the above numbered patent was erroneously issued to "Universal Oil Products Company, of Chicago, Illinois, a corporation of South Dakota", whereas said patent should have been issued to Universal Oil Products Company, of Chicago, Illinois, a corporation of Delaware, as assignee by mesne assignments, as shown by the records of assignments in this office; and that the said Letters Patent should be read with this correction therein that the same may conform to the record of the case in the Patent Office.

Signed and sealed this 17th day of November, A. D. 1936.

Henry Van Arsdale

Acting Commissioner of Patents.
